UNITED STATES PATENT OFFICE.

JOHN C. HEINRITZ AND JAMES WATSON MCCUEN, OF BALTIMORE, MARYLAND, ASSIGNORS OF ONE-THIRD TO RICHARD H. JOHNS, OF BALTIMORE, MARYLAND.

STREET-LAMP.

SPECIFICATION forming part of Letters Patent No. 697,717, dated April 15, 1902

Application filed September 21, 1901. Serial No. 76,016. (No model.)

To all whom it may concern:

Be it known that we, JOHN C. HEINRITZ and JAMES WATSON MCCUEN, citizens of the United States, residing at Baltimore, in the 5 State of Maryland, have invented certain new and useful Improvements in Street-Lamps, of which the following is a specification.

The accompanying drawings illustrate our improvement in hydrocarbon lamps for street-lighting, and the particular matters of novelty therein will be set out in the claims appended hereto.

In the drawings, Figure 1 represents a street-lamp embodying our improvement. 15 Fig. 2 is a vertical section of the burner part of the lamp. Fig. 3 is a like view of the globe part of the lamp.

The lamp shown is of two slidable frame parts to allow the globe-carrying frame part 20 to be lifted free of the burner; but our improvements are not confined to the particular lamp construction shown, and a brief description is only deemed necessary to show the application of our improvements to a 25 street-lamp in which the fixed part of the lamp-frame is formed by the standards 11 and the base-socket 2, the burner 3 being fixed between the standards and is provided with the usual adjustable needle-valve for 30 regulating the feed of the vapor and with the oil-supply branch pipe 4. A mantle 5 is suspended over the burner, and a chimney 6, seated upon the burner, incloses the mantle. A ring-tank 8, fixed on the upper ends of the 35 standards, supplies oil to the burner through one of the standards, the supply being controlled by the cock 7. Rods 9 are fixed to and rise from bosses 22 22 on the standards and form guides for the globe-containing 40 frame part.

10 is a ring which constitutes the movable frame part, and from it depend tubes 20 20, which are slidable over the rods 9 in raising and lowering the upper lamp part, said tubes 45 depending from bosses 21 21 on the outer walls of the ring 10. The ring has an inner ledge 11, on which the globe 12 is suspended by a rim 13, and an outer ledge 23, by which the ring is seated upon the oil-tank. The

dome 14 is seated and hinged by a base-ring 15 50 upon the ring 10. A convex reflector 16 is seated and hangs by a rim 17 upon the rim of the globe, and a draft-tube 18 passes through a central opening in the reflector and is suspended therefrom by a ring 19, clamped 55 upon the outer walls of the tube, and forms thereby a seat for the tube and closes the joint at the reflector-opening. The draft-tube extends above the reflector, and the adjustable ring-clamp suspending the tube from 60 the upper side of the reflector renders it convenient to raise and lower the draft-tube from the dome-space. Moreover, it will be noted that the draft-tube telescopes with the burner-chimney 6, and the tube being of greater diameter than the chimney leaves a space between the outer walls of the chimney and the inner walls of the tube and forms thereby a draft-space 25 to reinforce the usual draft at the base of the burner-chimney, giving there- 70 by an increased draft through the mantle and a more complete combustion within the mantle and a better light.

For adjusting the draft-tube it is only necessary to turn back the ventilating-dome, lift 75 the tube up, and set the clamp-band nearer to or farther from the upper end of the tube, so that it will form a greater or less prolongation of the burner-chimney, and in any adjustment of the draft-tube it maintains its 80 telescoping connection with the burner-chimney and extends above the reflector. This way of suspending the draft-tube from the reflector gives a true central seating to said tube in its telescoping relation to the burner- 85 chimney, and the projection of the tube through the ventilator prevents the diffusion of the products of combustion upon the globe-walls and the walls of the reflector.

A table 24, supported on the standards, 90 forms a seat for and closes the bottom of the globe.

The upper frame structure is lifted with the globe and the draft-tube to uncover the mantle and the chimney, and for this purpose the length of the rods 9 will be sufficient 95 to give a lift of about six inches. When the globe is so lifted, the tubes 20 will pass free

of and be supported on spring-detents 26, fastened on the rods, to hold up the movable globe-carrying frame part.

We claim—

- 5 1. In a lamp and in combination, a burner, a tank for supplying oil thereto, a globe and a reflector having a central opening, a draft-tube extending through the reflector, and a ring-clamp movable on the outer walls of the tube, freely seated upon the inner wall of the reflector closing the joint around its central opening and freely suspending said tube from the reflector.
- 10 2. In a lamp and in combination, a burner, a tank; for supplying oil thereto, a chimney

for the burner, a globe and a reflector having a central opening, a draft-tube extending through the reflector, means for adjustably suspending the tube from the reflector, said draft-tube being of greater diameter than the 20 burner-chimney, telescoping with it and forming a draft between the outer walls of the chimney and the inner walls of the draft-tube.

In testimony whereof we affix our signatures in presence of two witnesses.

JOHN C. HEINRITZ.

JAMES WATSON MCCUEN.
